WASTE PIPE PLUG

Robert G. Schwarz, New Orleans, La., and
Adolph H. Vorbusch, Pass Christian, Miss.

Application June 9, 1932. Serial No. 616,332

1 Claim. (Cl. 4—295)

The invention relates to all metal plugs particularly adapted for use in connection with drain openings of wash basins, sinks and the like, and has for its object to provide an all-metal plug 5 constructed in a manner whereby the same will be formed to the off-round shape of a drain opening when the plug is forced into the drain opening, thereby obviating the necessity of machine turning the drain opening ring opening and the 10 plug. It has been found that even where the drain opening ring is machined, it is often distorted to an off-round condition when applying the same in the basin.

A further object is to provide a plug comprising 15 a body member having a peripheral channel in which is loosely mounted an annular metallic ring, which ring will conform to the drain opening when the plug is forced into the opening, even if said drain opening is off-round.

20 A further object is to provide a metallic drainage opening plug comprising a body member having its periphery provided with an annular channel and a deformable metallic packing ring in said body member and formed from a different metal from the body member. Also to provide the packing ring with an inwardly extending flange extending into the body of the plug.

25 A further object is to first form the body member and then cast the ring in its annular channel from a different metal having a higher shrinkage coefficient whereby the ring, when cooled, will be free to rotate and flex when forced into a drainage opening.

30 A further object is to provide a metallic drainage opening plug constructed in a manner whereby it will conform to the drainage opening shape, and at the same time will be sanitary and eliminate packing material, for instance rubber or leather which are not sanitary, and which deteriorate, give off bad odors, and often stain articles in washing.

35 With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

40 In the drawing:

45 Figure 1 is a vertical transverse sectional view through the plug showing the same in a drainage opening.

50 Figure 2 is a top plan view of the plug.

55 Figure 3 is an enlarged vertical transverse sec-

tional view through one side of the plug to better illustrate the shrinkage clearance.

Figure 4 is a vertical transverse sectional view through a modified form of plug.

Figure 5 is a vertical transverse sectional view 60 through one side of the modified form of plug.

Referring to the drawing, the numeral 1 designates the body of the plug, which is preferably made from cast brass or aluminum. The body 1 is provided with the usual apertured lug 2 for the reception of the ring 3, to which a chain may be attached for pulling the plug from the drain opening 4 in the usual manner. The outer periphery 5 of the body 1 is provided with an annular channel 6 formed therein when the body 1 is cast from brass or aluminum or other metal.

It has been found that where metallic plugs for drainage openings are formed from a single piece of metal and are machined to a perfect 75 round condition for the round or machine drainage opening 4, the drainage opening ring 6a, often when placed in position is distorted and is off-round, therefore the machined plug does not closely fit and form a perfect seal, consequently there is a leakage. To obviate this 80 difficulty, after the plug 1 is cast with the annular channel 6 and the flange receiving channel 7 and 7a therein, a metallic packing ring 8 is 85 then cast in the annular channel 6. The ring 8 is cast from a different metal, preferably an alloy of brass and aluminum, and cast in a manner whereby when the metals contract, the ring 90 is loose to rotate as there is a space 9.

The shrinkage space 9 is shown slightly exaggerated to better illustrate the structure, however it will simply be a clearance sufficient for allowing a rotation of the ring, and at the same time allowing the same to be compressed so that it will conform to off-round shapes of the drainage opening 4. To better form a water tight seal, the inner periphery of the ring is provided with an inwardly extending flange 10, which fits into an annular groove 7 in the bottom of the recess 6. In the preferred form shown in Figures 1 to 3, the annular flange 10 is centrally disposed in relation to the upper and lower sides of the ring, while in the modified forms shown in Figures 4 and 5, the annular flange 10a is at the upper side of the ring 8, however the 100 operation of both forms is substantially the same, excepting there is more of a circuitous passage in one than in the other.

When the plug is forced downwardly into the drain opening 4, the ring 8 will flex so that it 110

will conform to the periphery of the drain opening 4. It will also be seen that by allowing the ring 8 to flex slightly in relation to the plug body 1, it will not work out of the drain opening 4 incident to temperature changes or to any rotation of the body 1.

From the above it will be seen that a drainage opening plug is provided which is formed from two pieces of metal having different characteristics as to shrinkage and the annular ring will conform to off-round shapes of drain openings. This is of particular advantage when it is considered that many of the drain opening rings 6a are at the present time being formed 15 from stampings and castings to eliminate machine work as far as possible.

The invention having been set forth what is claimed as new and useful is:

A drainage opening plug comprising a metallic body member having an annular channel in the periphery thereof, a metallic ring in said channel, a clearance between the ring and channel whereby the ring may conform in relation to the body member and a filling opening, said ring being formed from a different metal than the metal of the body member, said ring being cast in the channel and from a metal having a different shrinkage coefficient from the metallic body, whereby when it cools the clearance between the ring and channel is formed.
